VALVE

Application filed May 17, 1928. Serial No. 278,497.

The present invention relates to an improved valve for controlling fluid.

The objects of this invention are to provide a valve in which the valve face and the seat face can be easily ground, yet will be fully shrouded against the flow of fluid when the valve is wholly or partially open, and further will allow for a uniform increase in cross sectional opening of the valve, whereby a fine adjustment can be obtained.

The invention is more particularly described with reference to the accompanying drawings in which:—

Figure 1 is a sectional elevation of the valve.

Figure 2 is a detailed view on an enlarged scale.

The body of a stop valve 1 of any suitable form is provided with a detachable seat 20 formed of a ring piece 2 screwed into the usual web 3 of the valve. This ring piece 2 has a horizontal valve seating 4 which stands up away from the web piece 3, so that dirt and light material cannot accumulate upon 25 it, and further is shrouded on the inside by means of an upstanding vertical flange 5, which is adapted to pass into a recess 6 in the movable valve member 7, which member 7 has an external flange 8, the lower surface 9 30 of which is formed as a horizontal valve seating co-operating with the seating 4. These seatings are as shown, at right angles to the direction of displacement of the valve part 7 by means of the threaded spindle 10, and hand-wheel 11, so that they can be easily 35 ground.

The valve member 7 is provided with a hollow cylindrical extension 12 sliding within the annular seat member 2, and is provided 40 with a notch opening 13 of inverted triangular section, the apex 14 of which lies at some distance below the plane of the valve seating 9. It is preferred that the vertical distance 45 between the apex 14 and the valve seating 9 be greater than the depth of the flange 5, so that the seat elements 4 and 9 are well separated from one another, and this latter seating separated from its protective flange 5 before fluid commences to effectively flow 50 through the valve.

It will be seen by this construction that seatings on valve and body can be easily ground one upon the other, and yet are well protected from any possibility of accumulation of dirt upon them or from erosion by 55 flow of fluid across them. Further it will be seen that a very fine regulation of fluid flow can be obtained by this valve, and yet, the seatings are protected against the erosive action of fluid at high velocity passing across 60 them by means of the protection flange 5.

We declare that what we claim is:—

A valve comprising a body, a partition in said body, a removable annular member seated in said body and having a horizontal seating upstanding from said partition so that dirt cannot deposit on said horizontal seating, and having a vertical flange on the inner side shrouding said seating and upstanding therefrom, a valve member having a hollow cylindrical portion adapted to fit and slide inside said vertical flange and a horizontal valve seating to cooperate with said first horizontal seating, said valve member being provided between said horizontal 70 valve seating and said cylindrical portion with an annular recess to receive said upstanding flange, said cylindrical portion having a V notch therein with an upwardly directed apex located at a greater distance below said second horizontal seating than the depth of said upstanding flange so that in closing the V notch entirely enters within the vertical flange and thereafter said 75 seatings are brought together for a seal, and means for displacing said valve member with relation to said annular member to open and close the valve.

In witness whereof, we have hereunto signed our names this 16th day of March, 90 1928, and 3rd day of May, 1928, respectively.

JAMES EDWARD GRAINGER.

WENTWORTH GERRARD DIXON.
